IDENTIFICATION MARKER

Daniel I. Reiter, New York, N. Y.

Application March 1, 1933. Serial No. 659,046

18 Claims. (Cl. 40—143)

This invention relates to identification markers, and particularly, to that type which comprises an anchor member or supporting base provided with prongs adapted to be clenched through a layer of leather or fabric for the permanent attachment of the base to a bag, belt, garment or other suitable article to which attachment of the identification marker is desired.

The anchor member in such markers is adapted to carry a separately formed identification member bearing an identification character, such as a letter of the alphabet, a monogram, a number, a fraternal emblem, or any desired symbol. Each such identification member should be designed so that it may be applied to its anchor or base member by a retail merchant or sales person at the time of the sale of a bag or other article, and without the necessity for skilled operation or the use of expensive equipment.

My invention contemplates the provision of a simple, inexpensive and efficient form of anchor member, readily formed from sheet-metal, and which is adapted to serve without alteration to receive any selected identification member from a very extended series available for identification purposes such as those above mentioned.

My invention further contemplates the provision of auxiliary anchor members similar in construction to that of the permanently attached anchor members, but adapted to be attached readily, in extension of any such permanently attached anchor member, by a retail merchant, sales person, or other person having but average mechanical skill, when a customer desires to have more than one identification character upon the article purchased, as for example, two or three initials of a name.

My invention contemplates further, the provision of an improved type of identification member adapted to be attached interchangeably upon any of the permanently attached anchor members or auxiliary anchor members, and embodying integrally formed means to effect such attachment easily and in a manner which prevents accidental displacement of the identification member, but will permit intended removal thereof when desired.

My invention further contemplates the use of a single anchor member and an overlying identification member secured thereto, or a main anchor member with its overlying identification member, and one or more auxiliary anchor members, each with its corresponding overlying identification member, designed to be attached to meet the individual requirement of a purchaser.

The various objects of my invention will be clear from the description which follows, and from the drawing, in which,

Fig. 1 is a plan view of an identification marker embodying the invention, applied to one face of a flexible sheet, such as a purse or the like, and comprising an anchor member and an identification member.

Fig. 2 is a similar plan view of a group of identification markers applied to part of a flexible sheet and comprising a permanently attached anchor member, two auxiliary anchor members, and three identification members, combined as provided by this invention.

Fig. 3 shows separately, in perspective, the anchor member which is to be permanently attached.

Fig. 4 is a similar view of my new auxiliary anchor member of the standard form which I have provided, and adapted to be applied at either side of the permanently attached anchor member of Figs. 1 to 3.

Fig. 5 is a vertical section of the marker as it appears in operative position and taken on the line 5—5 of Fig. 1.

Figs. 6, 7 and 8 are similar fragmentary detail views showing modified forms of the means for effecting attachment of the identification members to any of the anchor members.

Fig. 9 is a fragmentary horizontal section, taken on the line 9—9 of Fig. 1.

Figs. 10, 11 and 12 are fragmentary detail views of my invention in plan, each showing a different arrangement of several identification members upon the anchor members shown in Figs. 1 to 3.

In the practical embodiments of my invention which I have illustrated by way of example, pronged anchor members and hooked identification members of now-preferred form are illustrated, it being intended that at least one of the anchor members be secured in place before the article to which it is attached is finished, and that the identification member be arranged in place on the anchor member to meet the desire of the purchaser.

Referring particularly to Figs. 1 to 5 inclusive, and Fig. 9, the anchor member 11 to be permanently attached to any selected article is preferably made of sheet material and is provided with attaching prongs 12 integral therewith, and adapted to penetrate the leather or fabric layer 13 which in the instance illustrated, is formed by the outer wall of a purse, of which enough is illustrated to show the mode of attachment. The prongs 12 are clenched over by any suitable tool

on to the inner face of the sheet 13, being bent preferably toward each other. In Figs. 5 and 9, an inner lining comprising for example, the reinforcing sheet 14 and the silk lining 15, both of which are of conventional form in the instance shown, and are optional, serve to finish the sheet and to complete the article, and also, to conceal the prongs 12.

The anchor member 11 shown in Figs. 1 and 3 is provided with an integral marginal flange 16, extending rearwardly at right angles to the body of the member 11 and preferably extending entirely around the periphery of the member, the flange being slotted at suitable intervals to form side recesses or slots 17 and end recesses or slots 18, for the purpose soon to be described. The depth of the flange 16 may be varied suitably to cause the body portion 11 to be presented at the desired height from the sheet 13.

Said anchor member 11 may be secured to the purse 12 or other article, in the manner described, at the factory or at any time prior to wholesale delivery of the articles, whatever their character, and it is intended that the manufacturer or wholesale dealer furnish each retailer with a suitable quantity of identification members of varied character, designed to meet the demands of fashion and according to the nature of the identification for which provision is to be made. For example, sets of letters of the alphabet, monograms, members, and/or any desired symbol or symbols may be so furnished.

Each of the identification members is adapted for combination interchangeably with any anchor member 11, and in pursuance of the invention, the respective identification members, herein designated generally by the reference numeral 19, are provided with means to permit them to be secured readily and firmly in place by a retail dealer or by the user, so that accidental displacement in use will be prevented, but intended removal may be accomplished, if desired.

As a convenient form of securing means, I have provided one or more bent hook-like projections 22, 23, preferably formed integrally with the sheet metal of the identification character, and so disposed as to be adapted to engage the lower margin 20 of the anchor member at the lower slots 18, which are adapted to receive the end portions of the hooks 22 and 23.

Said slots 18 are so spaced that the letter or other identification character, for example, the letter "L" shown in Fig. 1 is held firmly in place, cooperating with the resilient upper hook 21 for that purpose. The upper hook 21 engages the upper end 20 of the anchor member, and the lower hooks 22 and 23 engage the lower end 20 thereof, the hooks 21, and the hooks 22 and 23 being separated transversely from each other at a distance suitable for each hook to select and enter one of the recesses 18 formed in the margin of the anchor member for that purpose.

The hooks 21, 22 and 23, or any suitable hook devices at selected portions of each identification member are preferably so formed as to facilitate either a snapping engagement or a hooking action, as desired. All of said hooks or only the set on one edge of letter or character may therefore be made resilient. One or more of the retaining devices, as for example, that designated 21, in opposed relation to the hooks 22 and 23, is preferably of a structure designed to adapt it to snap around the margin 20.

Various forms of the snap-fastening device 21

may be adapted to accomplish this object of the invention, and I have shown several illustrative forms or modifications of the same in Figs. 6, 7 and 8, wherein each of the figures represents a device 21 in the position shown in Fig. 1, at the top end of a letter, although a snap device, or any suitable number of such devices, constructed as in any of these figures, may be located elsewhere upon the identification member. Obviously, a letter, or other character, like the letter "I" or the numeral "1", or the top of the letter "L" or bottom of the letter "T" may be formed to need only one hook 22 and/or one snap-fastening device 21, and can be so formed. The letters illustrated throughout the drawings are of skeleton form, or outlined in metal, this being an attractive form of letter for such display purposes as those required for purses and the like, but this skeleton form is not necessarily required.

Referring more particularly to Figs. 1, 5 and 6, the device 21 shown therein is preferably, as has been indicated, a snap fastening device, extending at approximately right angles to the body of the identification member 19 and having a slightly bevelled lower edge to aid in easing it by a cam-like action over the margin 20a of the member 11. The margin 20a may desirably be rounded to facilitate this application of the snap device, which has a sufficient inclination downwardly to cause it to enter one of the end recesses 18, and to be held therein against lateral or transverse displacement. The hooks 22 and 23 at the opposite end of the identification member may be first entered into the lower recesses 18, the upper end of said member being held away from the member 11 until said hooks are in place and said member then turned or rotated against the member 11 about the hooks 22 and 23 as a pivot until the hook 21 snaps into place. Since the hooks 22 and 23 each enter one of the end recesses 18 in the bottom flange 20 of the anchor member 11, and as these end hooks and the snap device 21 are converged relatively to each other, they cooperate in clamping the identification member firmly to the anchor member.

The complete marker, as shown clearly in Fig. 1, displays its identification character "L" attractively in relief upon the flat base afforded by the anchor member 11, and presents a neat, attractive appearance. It is easy to clean and polish, and the anchor member is free from surface recesses likely to accumulate dust.

The spacing of the end recesses 18 is such that any letter of the alphabet provided with the hook devices 22 and 23 and the snap device 21 will be held in alignment with the anchor member, as appears clearly upon observation of the letters "D", "M", and "T", shown respectively in Figs. 10, 11 and 12.

As already mentioned briefly, the snap hooks 21 may be of various modified forms, and in the two illustrative modifications shown in Fig. 7 and Fig. 8, I have indicated how such modifications may desirably be made.

That shown in Figs. 7 illustrates a snap device, designated 21a, the extreme end of which is bent below the remainder thereof to form a pocket or recess into which the marginal portion 20a of the member 11 snaps, after said extreme end has passed the margin during its inward movement.

It will be seen that at the completion of said movement, said extreme end is released or moves downwardly to hold the margin in the recess thus formed.

In Fig. 8, the projection 21b extends at right

angles to the body 19 of the identification member, and has a re-entrant prong or finger 21c inclined downwardly toward the body part 19 and presents an inclined nose which aids in snapping it over the margin 20a and into the flange recess 18. This part 21c acts positively to resist displacement. This form has the advantage, desirable in some applications, of being permanent, as it is difficult to displace, even by intention.

10 Passing now to a further feature of my invention, I have provided auxiliary anchor members which can be applied easily and quickly by a retail dealer or user, to furnish an extended base for the display of added initials of a person's name, or other identification members of any suitable character.

These auxiliary members 24 are preferably of standardized form, similar in general appearance to that of the anchor member 11 already described, and adapted to be applied in cooperation therewith, utilizing the lateral recesses 17 in the side portions of the marginal flange 16 already mentioned in describing what may be termed the "main" anchor member 11, the latter being designed preferably as a permanent fixture on the sheet 13.

To accomplish the above aim, each auxiliary member 24 is provided with suitable lugs or projections 25. Said projections extended laterally from one side of the member 24 at the same time that a flange 26 is struck up from the body of the member 24. The lugs 25 are so spaced relatively to each other, and extend in such a plane, parallel with said body that they may be readily inserted in the side recesses 17 of the main anchor member 11 by a single movement, occupying the position shown in Figs. 1 and 9.

These lugs, and the flange 26, which rests against the sheet 13 parallel with the flange 16 of the main member, and contiguous thereto, coact to maintain the body 24 of each auxiliary anchor member flush with the body 11 of the main anchor member. In order to secure such auxiliary member in this relationship, I provide suitable means to fasten it to the sheet 13.

As a now-preferred form of such means, I have illustrated prong fastening devices 27 conveniently struck up as preferably integral portions of an extension 28 of the flange 26, these prongs, as clearly shown in Fig. 4, being adapted to be thrust through the sheet 13 and the lining members 14 and 15, and then clenched over as indicated in Figs. 1 and 9.

This operation does not involve any special skill, and can be accomplished quickly and accurately, at the time of sale of a purse or other article to a retail customer, by a sales person, who can then apply to the auxiliary anchor member thus affixed, any selected initial or other identification member in stock. Each auxiliary anchor member has recesses 18 in the end portions of its marginal flange, corresponding in function and position to those in the margin 20 of the main anchor member.

65 In applying the identification letters, "A", "L", "T", for example, on the anchor members 11 and 24 of Fig. 1, the sales person or other operative will insert the lower end hooks 22 and 23 of the letter "A" in the correspondingly spaced slots 18 at the bottom of the left hand auxiliary anchor member 24 and press the letter A against the body of that anchor member until the snap device 21 snaps over the upper margin and into the middle recess of the series 18 in the upper end flange 26. Then, the letter "L" will be similarly

applied to the main anchor member, and the letter "T" to the right-hand auxiliary member.

In this connection, it is to be noted that the auxiliary anchor members 24, being all preferably of standard form, as already described, and as illustrated in Fig. 4, need only be turned end for end to permit application to one side or the other of the main anchor member 11, so that only one type need be kept in stock to furnish any article with one or with two added anchor members and identification letters.

It will also be apparent that the identification members can be provided with a snap hook at either top or bottom, as shown in the case of the letter "T", which has a pair of snap devices 21 at its top, and "hook-on" hooks 22 and 23 at its lower end. Of course, both of the retaining devices may be of the snap variety, and this need not be described in detail.

The letters may be applied in different groupings, as illustrated in Figs. 10, 11 and 12, simply by inserting the lugs 25 of the auxiliary anchor members 24 in the proper side recesses 17 of the main anchor member.

I contemplate the provision of auxiliary anchor members in addition to those shown, to any extent which may prove desirable, it being only necessary for this purpose to provide the flanges 26 with lateral recesses such as shown at 17 in Fig. 4.

It will be readily understood from the foregoing specification that in carrying the same into effect, as described, I have provided means for securing identification members to a flexible sheet or article, whereby a base is first secured to the sheet, and a character member is then attached to the base by first hooking the members together at one end, and then by a single movement, swinging the identification member into its final position without the necessity for bending down lugs or clamping acts of any kind. My new device may be used to secure any number of characters in varied relation by interlocking auxiliary base members therewith and attaching a character to each base member.

By full utilization of the invention, therefore, it is possible to fabricate, at relatively low expense for materials, and without highly skilled labor, an equipment comprising identification markers including a multiplicity of main anchor members and readily interlocked auxiliary anchor members, with a multiplicity of identification members, each marker, when applied, being displayed in securely attached position upon a purse or other article, and presenting an attractive appearance.

While I have shown and described certain specific forms of my invention, I do not intend to be understood as limiting myself thereto, but desire to claim my invention as broadly as is permissible in view of the state of the prior art and the terms of the appended claims.

I claim:

1. The combination with a flexible sheet, of an anchor member secured to the sheet, an identification character having a plurality of spaced laterally extending projections, certain of said projections being adapted to be engaged retentively with the marginal portion of said anchor member, at least one of said projections being yieldable and adapted to snap resiliently into anchored position.

2. In a marker, an anchor member provided with attaching means whereby it may be secured to a flexible support, and having an anchorage

- margin, and an identification member adapted to be assembled with said anchor member and having a plurality of laterally projecting bent retaining hooks for engagement with said anchorage margin, at least one of said retaining hooks being formed to be hooked on said anchorage margin by a relative lateral sliding movement of said members, and another of said retaining hooks being resilient to snap past said anchorage margin when said members are pressed together. 80
3. In a marker, an anchor member provided with bendable attaching means whereby it may be secured to a support, and having a marginal flange provided with anchorage recesses, and an identification member adapted to be assembled with said anchor member, said identification member having a plurality of spaced hooks adapted to enter correspondingly spaced anchorage recesses in the flange of said anchor member, at least one of said hooks being adapted to be snapped past a marginal anchorage recess of said flange at a region oppositely disposed with respect to others of said hooks. 85
25. 4. In a marker, an anchor member formed of sheet material and having a body portion terminating in a marginal flange extending rearwardly into position to engage a support and provided with spaced anchorage recesses, said anchor member having prongs adapted to transfix the material of the support and to be clenched thereto, and an identification member comprising a letter or like identification character provided at one end with a laterally extending hook adapted to be hooked into an anchorage recess, said character having at its other end a resilient projection adapted to be snapped into an anchorage recess in the marginal flange at the corresponding end of said anchor member. 90
30. 5. The combination with a flexible non-metallic member, of a metallic anchor member having marginal flanges, an identification member comprising a sheet metal character in the form of a letter of the alphabet or like symbol, marginal means on the identification member for removably securing the identification member to the flanges of the anchor member, and means for securing the anchor member to the flexible member. 95
35. 6. The combination with an anchor member having marginal means for attachment to a flexible non-metallic support, of an identification member comprising a sheet metal character in the form of a letter of the alphabet or like symbol, having marginal means for securing the identification member to the anchor member. 100
40. 7. The combination with a flexible non-metallic support, of an anchorage member secured to the support, and an identification member comprising a character made of sheet-metal in the outline of a letter of the alphabet or like symbol, having a pair of opposed hooks projecting therefrom, said hooks being bent rearwardly and toward each other and adapted to be secured to the cooperating anchorage member by a single movement. 105
45. 8. The combination with a flexible non-metallic support, of a sheet metal supporting member secured to the support and adapted to serve as a base for an identification member, and an identification member comprising a flat sheet metal body portion shaped to form a symbol and having at one end a hook extending rearwardly from the plane of the body portion and adapted to be hooked about the edge of the cooperating sheet metal supporting member, said body portion having at its other end a snap-fastening device comprising an extension projecting rearwardly from the body portion and convergently with respect to said hook, and being adapted to engage yielding a marginal portion of said sheet metal supporting member opposite to that engaged by said hook, and to act in cooperation with said hook to embrace said supporting member. 110
50. 9. An identification marker comprising a supporting member having laterally extending marginal flanges, an identification member comprising a sheet metal symbol, fastener means integral with and projecting rearwardly from the identification member at the ends thereof and adapted to assume a position rearwardly of the rear face of the supporting member to resist positively displacement of said identification member from said supporting member, and rearwardly projecting prongs on the supporting member for securing the supporting member to a flexible article and thereby to secure identification member to the article. 115
55. 10. In an identification marker, an anchor member formed of sheet metal, a rearwardly directed marginal flange provided with anchorage recesses projecting from and integral with said member, and an identification member having opposed hooks, at least one of which is resilient and adapted respectively to embrace opposite marginal portions of said anchor member, each of said hooks entering a recess in the contiguous portion of said flange, transverse displacement of said identification member relatively to the anchor member being prevented by engagement of the hooks with the walls of the corresponding recesses and bodily relative displacement of the members being resisted by the frictional engagement of said hooks with the contiguous portion of said anchor member. 120
60. 11. A marker equipment comprising a multiplicity of similar anchor members formed respectively, of sheet metal and each provided with an elongated body portion having integral marginal anchorage flanges and attaching means, and a multiplicity of identification members each comprising a letter of the alphabet or like symbol formed of sheet metal and provided with laterally extending end hooks, said identification members being mutually interchangeable throughout each series, by the engagement of each hook, with said anchorage flanges. 125
65. 12. In a marker, a main anchor member having means for attachment to a supporting article and adapted to serve as a base for an identification member, and a separately formed auxiliary anchor member having means for attachment to said supporting article and to the main anchor member, and adapted to serve as a base for another identification member, adjacent to, and in extension of, said main anchor member. 130
70. 13. In a marker, a main anchor member having means for attachment to a supporting article and adapted to serve as a base for an identification member, and a separately formed auxiliary anchor member having means for attachment to said supporting article, and adapted to serve as a base for another identification member, adjacent to, and in extension of, said main anchor member, said main and auxiliary anchor members being respectively provided with mutually interconnecting means to maintain said members in assembled relation, and each of said members having marginal flanges adapted for re- 135
75. 14. A marker equipment comprising a multiplicity of similar anchor members formed respectively, of sheet metal and each provided with an elongated body portion having integral marginal anchorage flanges and attaching means, and a multiplicity of identification members each comprising a letter of the alphabet or like symbol formed of sheet metal and provided with laterally extending end hooks, said identification members being mutually interchangeable throughout each series, by the engagement of each hook, with said anchorage flanges. 140
80. 15. A marker equipment comprising a multiplicity of similar anchor members formed respectively, of sheet metal and each provided with an elongated body portion having integral marginal anchorage flanges and attaching means, and a multiplicity of identification members each comprising a letter of the alphabet or like symbol formed of sheet metal and provided with laterally extending end hooks, said identification members being mutually interchangeable throughout each series, by the engagement of each hook, with said anchorage flanges. 145
85. 16. A marker equipment comprising a multiplicity of similar anchor members formed respectively, of sheet metal and each provided with an elongated body portion having integral marginal anchorage flanges and attaching means, and a multiplicity of identification members each comprising a letter of the alphabet or like symbol formed of sheet metal and provided with laterally extending end hooks, said identification members being mutually interchangeable throughout each series, by the engagement of each hook, with said anchorage flanges. 150

tentive engagement with any of a multiplicity of similar identification members.

14. In a marker, a main anchor member having means for attachment to a supporting article 5 and adapted to serve as a base for an identification member, said main anchor member having a marginal flange provided with a series of recesses adapted to receive corresponding lugs upon an auxiliary anchor member.

10 15. In a marker, a main anchor member of a single piece of sheet metal having a marginal flange provided with a series of recesses adapted to receive corresponding lugs upon an auxiliary anchor member, and disposed at either side of 15 said main anchor member.

16. In a marker, a main anchor member having a marginal flange provided with a recess, and an auxiliary anchor member provided with a transversely extending connecting lug entering 20 said flange recess, said auxiliary member being adapted to serve as an extension base for an added identification member.

17. An auxiliary anchor member, for use in

an identification marker, provided with a main recessed anchorage member adapted to serve as a base for an identification member, said auxiliary anchor member comprising a body portion adapted to serve as a base for an identification member in addition to that supported on said main anchor member, and lugs extending from said auxiliary anchor member and suitably spaced to enter selectively any of the recesses of said main anchor member, whereby said auxiliary member is connectable to said main anchor member in a variety of positions to permit display of a plurality of identification members in correspondingly varied groupings.

18. In a marker, an anchor member provided with marginal recesses, means for securing the member to a sheet, and an identification member provided with projections adapted to enter the recesses of the anchor member to permit the members to be secured together in face to face relation by a single swinging movement.
